UNITED STATES PATENT OFFICE

148,415

DESIGN FOR A WHEELED FIRE EXTINGUISHING UNIT OR SIMILAR DEVICE

Henry R. Harper, Evanston, Ill., assignor to Cardex Corporation, Chicago, Ill., a corporation of Illinois

Application July 3, 1946, Serial No. 131,319

Term of patent 14 years

(Cl. D14—3)

To all whom it may concern:

Be it known that I, Henry R. Harper, a citizen of the United States, residing at Evanston, in the county of Cook and State of Illinois, have invented a new, original, and ornamental Design for a Wheeled Fire Extinguishing Unit or Similar Device, of which the following is a specification, reference being had to the accompanying drawing, forming part thereof.

Figure 1 is a perspective view of a wheeled fire extinguishing unit showing my new design,

Figure 2 is a top plan view of the same,

Figure 3 is a side elevational view of the fire extinguishing unit, and

Figure 4 is an end elevational view of the unit.

The characteristic features of my design reside in the portions shown by means of full lines in the drawings.

I claim:

The ornamental design for a wheeled fire extinguishing unit or similar device, substantially as shown and described.

HENRY R. HARPER.
